SHOCK ABSORBER

Frederick E. Cusack, Okmulgee, Okla.

Application May 9, 1936, Serial No. 78,948

4 Claims. (Cl. 255—16)

This invention aims to provide a novel shock absorber, adapted to be interposed between the bull wheel and the crank shaft, in known constructions wherein the crank shaft is disposed between the bull wheel and the hole that is being formed by well-drilling apparatus.

The invention aims to improve the construction of the shock absorber and to provide novel means for mounting and sustaining it.

It is within the province of the disclosure to improve generally and to enhance the utility of devices of that type to which the invention appertains.

With the above and other objects in view, which will appear as the description proceeds, the invention resides in the combination and arrangement of parts and in the details of construction hereinafter described and claimed, it being understood that changes in the precise embodiment of the invention herein disclosed, may be made within the scope of what is claimed, without departing from the spirit of the invention.

In the accompanying drawings:

Figure 1 shows, in side elevation a portion of a well-drilling apparatus equipped with the device forming the subject matter of this application;

Figure 2 is a longitudinal section of the shock absorber;

Figure 3 is a top plan wherein parts have been broken away;

Figure 4 is a longitudinal section of one of the braces;

Figure 5 is an elevation showing how the braces may be mounted at their lower ends.

The device forming the subject matter of this application is adapted to be used in connection with many known well-drilling machines of that general type in which the crank sets between the bull wheel and the hole that is being drilled. One form of a machine of that kind is shown in Fig. 1 of the drawings, but the invention is not confined to use with the particular machine delineated.

The numeral 1 marks a foundation, generally made of timber, and carrying a derrick 2. A means 3 is provided for supporting for rotation, the shaft 4 carrying the band wheel 5. A crank 6 is secured to the shaft 4. A shaft 7 is mounted on the crank 6, in adjusted positions longitudinally of the crank, the crank 6 being provided with means 8 whereby the aforesaid adjustment of the shaft 7 may be brought about. A grooved pulley 9 is journaled for rotation on the shaft 7. The foundation 1 carries a means 10 for sup-

porting the bull wheel shaft 11 for rotation, the bull wheel being marked by the numeral 12. The line 14 is engaged around the drum of the bull wheel shaft 11 and passes around the crank pulley 9, to the upper end of the derrick 2, and downwardly into the hole that is being drilled or worked otherwise.

The parts hereinbefore described are known and common, and no novelty is claimed for them saving insofar as they may enter into combination with parts hereinafter described.

In carrying out the invention, there is provided a telescopic post 15, including a lower tubular member 16 having a foot plate 17 secured to the foundation 1, between the bull wheel 12 and the crank shaft 7. An upper tubular member 18 is mounted for vertical reciprocation in the lower tubular member 16 and is provided with a bottom 19. Oil may be introduced into the lower part of the lower tubular member 16, to lubricate the springs hereinafter mentioned, and to facilitate the vertical sliding movement of the upper tubular member 18. With this end in view, the lower tubular member 16 is supplied with a filling and drain plug 20, shown in Fig. 2 of the drawings.

The lower end of a stem 21 is secured at 22 to the foot plate 17, which closes the lower end of the lower tubular member 16. The stem 21 passes slidably through the bottom 19 of the upper tubular member 18, and extends upwardly into the upper tubular member. A rebound spring 23, which is a compression spring, is disposed within the upper tubular member 18, about a portion of the stem 21. The lower end of the spring 23 abuts against the bottom 19 of the upper tubular member 18. The upper end of the spring 23 abuts against a washer 24 on the stem 21. A tubular spacer 25 is placed on the upper part of the stem 21, the lower end of the spacer 25 engaging the washer 24. A washer 26 is mounted on the upper part of the stem 21 and engages the upper end of the spacer 25. Superposed nuts 27 are threaded on the upper end of the stem 21, the lowermost nut engaging the washer 26. The nuts 27 constitute means for adjusting the effort of the spring 23, in a way which will be understood readily when Fig. 2 of the drawings is noted. Parallel guide plates 28 are mounted in the upper end of the upper tubular member 18 and extend across the same. In the guide plates 28 and in the upper tubular member 18, a shaft 29 is mounted. A grooved pulley 30 is journaled on the shaft 29 and operates between the guide plates 28. The line 14 passes along the tread of

the grooved pulley 30, as clearly shown in Fig. 1 of the drawings.

An outer compression spring 31 is located in the lower tubular member 16, and an inner compression spring 32 is arranged within the outer compression spring 31. The springs 31 and 32 are disposed about the lower portion of the stem 21. At their lower ends, the springs 31 and 32 abut against the foot plate 17. At their upper ends, 10 the springs 31 and 32 abut against the bottom 19 of the inner or upper tubular member 18, and, therefore, support it for vertical yielding movement.

Longitudinally adjustable braces 33 are provided. Each brace 33 includes a lower outer tubular member 34, provided at its lower end with a reduced fin 35 connected by an attaching element 36 to an ear 37 at the end of an anchor strip 38 secured to the foundation 1. An upper 20 tubular member 39 has limited movement in the lower or outer tubular member 34 of each brace 33. The ends of a cross bolt or stop 40 are mounted in the lower member 34 of each brace, near to the upper end of the said member. Each 25 upper tubular member 39 has oppositely disposed elongated longitudinal slots 41, through which the stops 40 pass, relative longitudinal movement between the members 39 and 34 of the brace thus being possible. An abutment pin 42 is mounted 30 in the upper tubular brace member 39, above the lower brace member 34. A washer 43 surrounds the upper tubular member 39 and abuts against the pin 42. A compression spring 44 surrounds a portion of the upper tubular brace member 39. 35 The upper end of the spring 44 engages the washer 43, and the lower end of the compression springs engages a washer 45 mounted on the upper tubular member 39 and having a bearing on the upper end of the lower tubular member 34. 40 Connectors 46 are threaded for adjustment into the upper ends of the parts 39 of the braces 33 and are held in adjusted positions by superposed nuts 47 threaded on the connectors 46, the lowermost of the said nuts engaging the upper ends 45 of the brace members 39. The connectors 46 have flattened ends 48 connected by attaching elements 49 with offset brackets 50 carried by the lower member 16 of the post, near to the upper end of the said member.

50 Without extended explanation, and simply by an examination of Fig. 2 of the drawings, it will be obvious that the upper tubular member 18 of the post 15 can move downwardly with respect to the lower member 16 of the post, responsive to 55 downward pressure exerted by the line 14 on the pulley 30 that is carried by the upper portion of the post. The downward movement of the upper portion 18 of the post is checked yieldably by the springs 32 and 31, and any rebound that 60 may occur is taken care of by the spring 23, the construction being such that the line 14 will not jump out of the grooved pulley 30. The inclined braces 33 are adjustable for length, by rotating the connectors 46 and by holding them in adjusted positions through the instrumentality of 65 the nuts 47. The springs 44 permit the upper brace members 39 to have a yieldably restrained longitudinal movement with regard to the lower brace members 34.

70 The shock absorber forming the subject matter of this application is well made and thoroughly adapted to withstand long continued and hard use, without expert attention. Wear is cut down, owing to the presence of the oil in the lower post

member 16. If an operator is caught in any of the working parts, the device forming the subject matter of this application will prevent him from being subjected to serious injury.

The device is easily set up and saves time in 5 hooking on, to start spudding. The number of working parts is cut down to a minimum, and wear and cost of material is decreased accordingly. Should the springs 31 or 32 break, they will still be held in position and will continue, to a 10 considerable degree, to exercise their function. There is practically no limit to the depth of the hole that can be drilled or worked upon when a drilling machine is equipped with the device 15 forming the subject matter of this application. The structure will operate in a satisfactory way in connection with any standard machine in which the crank is located between the bull wheel and the drill hole.

The braces 33, although useful, do not have 20 much strain put on them. The post 15 carries most of the strain, and it is in the form of a vertical, downward thrust, running from one to three tons, especially in deep drilling. This causes the post 15 to settle some, and a brace of 25 fixed length will bend. In view of the foregoing, the utility of the telescopic braces 33 and the springs 44 will be appreciated readily.

Having thus described the invention, what is 30 claimed is:

1. In a well-drilling mechanism, a bull wheel shaft and a crank member spaced from the bull wheel shaft, a line extending from the bull wheel shaft across the crank member, and a shock absorber mounted between the bull wheel shaft and 35 the crank member and comprising a resiliently supported part across which the line passes.

2. In a well-drilling mechanism, a bull wheel shaft and a crank member spaced from the bull wheel shaft, a line extended from the bull wheel 40 shaft across the crank member, a telescopic post mounted between the bull wheel shaft and the crank member and comprising upper and lower portions, means for supporting the upper portion of the post yieldably, and means carried by the 45 upper portion of the post for engaging the line at a place between the bull wheel shaft and the crank member.

3. In a well-drilling mechanism, a shock absorber comprising telescopic upper and lower 50 members, means on the upper member for carrying a line, resilient means for urging the upper member upwardly, a brace having its upper end connected to the lower member of the post, the brace comprising parts having relative longitudinal 55 movement with respect to each other, spring means for limiting said movement of the parts of the brace, and means for adjusting the length of the brace.

4. In a well-drilling mechanism, a shock absorber comprising telescopically connected upper and lower members, means on the upper member for carrying and guiding a line, a stem connected to the lower member and extending upwardly into the upper said member, a first compression spring about the stem and interposed between the lower end of the lower member and the lower end of the upper member, a second compression spring about the stem and disposed in the upper member, the lower end of the second spring abutting against the lower end of the upper member, and an abutment on the stem and engaging the upper end of the second spring.

FREDERICK E. CUSACK.
